SPOOL OR BOBBIN FOR THREAD, RAYON,
YARN, OR THE LIKEJohn Edward Lock, St. Charles De Mandeville,
Quebec, Canada, assignor of one-half to J. Ard
Haughwout, Montclair, N. J.

Application April 4, 1939, Serial No. 265,959

6 Claims. (Cl. 242—122)

The invention relates to improvements in spools and bobbins for thread, rayon, yarn, and the like, as described in the present specification, and illustrated in the accompanying drawing that forms part of the same.

The invention consists essentially in devising a spool in which the barrel or cylinder may consist of a cardboard, paper, or other similar substance and in forming the base or bases for the barrel or cylinder of a more durable substance such as wood and in locking the two together to complete an integral spool, as pointed out broadly and specifically in the claims for novelty following a description in detail of an acceptable form of the invention.

The objects of the invention are to devise a satisfactory spinning and winding bobbin or spool for thread, silk, rayon, yarn, and the like, which will be both light and strong and will run true on account of being perfectly balanced; to avoid vibration during the use of the spool or bobbin and consequently decrease the wear of the spindle; to assure a better wound spool or bobbin and thereby save a waste of time and thread, and in view of the lightness and strength of the spool, enable the spool to run at high speed more so than an ordinary bobbin or spool which is made of heavier construction, and generally to provide a spool that will be durable in construction and efficient for its use.

In the drawing,

Figure 1 is an elevation of a spool or bobbin showing the thread as applied thereto.

Figure 2 is an elevation of the spool or bobbin without the thread.

Figure 3 is a vertical sectional view as taken on the lines 3—3 in Figure 2.

Figure 4 is an elevation of a spool or bobbin having the closure cut inserted therein.

Figure 5 is an elevation of the double spool or bobbin.

Figure 6 is a vertical sectional view as taken on the lines 6—6 in Figure 5.

Figure 7 is a cross sectional view as taken on the lines 7—7 in Figure 5.

Figure 8 is a cross sectional view as taken on the lines 8—8 in Figure 5.

Like numerals of reference indicate corresponding parts in the various figures.

It is well known in the art to have wooden spools or bobbins but these are too heavy and expensive for this purpose, whilst a spool made of all paper is not strong enough for this purpose, and furthermore in the heavier type of bobbin, this has the effect of causing the wear-

ing of the spindle of the machine to which it is applied, and it is therefore among other features of this invention to combine all the effectiveness of the light bobbin or spool and add thereto all the durability of the heavier bobbin or spool, in other words, by utilizing the barrel made from cardboard and adding thereto a base made from wood or the like, and devising a means for locking the two together so that the barrel will not pull out in either one or the other direction, a true balanced bobbin or spool is constructed, and in the accompanying drawing and following description an acceptable type of spool or bobbin utilizing the locking feature is utilized.

Referring to the drawing, the spool or bobbin consists of a tubular barrel member as indicated by the numeral 10, which is made of suitable material such as paper, cardboard or the combination of paper and cardboard, and one end of the barrel is flanged outwardly to form a generally conical flange as indicated by the numeral 11. The base 12 is preferably made of wood or of other suitable substance heavier than the material of the barrel. This base is provided with a generally cylindrical orifice 13 therethrough outwardly from which is formed the generally conical seat 14 preferably shaped to conform with the flange or the flaring out portion of the barrel.

The plug or bushing 15 which may be made of wood or other substance is chamfered at one end into generally conical form so as to conform with the inner surface of the flange 11 of the barrel, and in this way it will be seen that the end of the barrel is thoroughly locked within the base 12 by means of the bushing 15 which forms a tight fit within the base, and at the same time tightly squeezes the end of the barrel between the bushing and the base.

It will be noted that the plug or bushing 15 fits tightly within an enlarged orifice in the base 12 so that the end of the flange 11 of the tubular barrel is entirely concealed from view by means of the base 12 and the plug or bushing 15. The end of the spool will therefore present a continuous surface of wood or the like.

In the type of spool or bobbin as described in Figures 5 and 6, the same construction is shown with the exception that the head 16 of the spool is shaped slightly differently from the base, and also is provided with the orifice and a conical seat 17 for the purpose of engaging with the flared ends 18 of the cardboard barrel 19. In this case, the bushing 20 is in the form of a flanged head which is adapted to engage with 55

the seat 17 of the head and also to engage with the flaring end of the barrel, and extends downwardly into the barrel in the form of a sleeve 21 which is for the purpose of giving additional strength to the structure, and it will be seen that the general feature of locking the head to the barrel is the same as the way in which the base is locked to the lower end of the barrel.

It will therefore be seen that one of the essential features of this spool or bobbin is in the way in which the cylinder or barrel is made of paper-board and is locked in a rigid position with the base made from wood or heavier material than the barrel, and in that way there is absolutely no danger of the barrel detaching itself from its base while in use or otherwise, and at the same time enable the proper balance for these spools which is quite important in their uses.

20 It will be noted that the constructions shown and described will serve admirably to accomplish the objects stated above. It is to be understood, however, that the constructions disclosed above are intended merely as illustrative of the invention and not as limiting as various modifications therein may be made without departing from the invention as defined by a proper interpretation of the claims which follow.

What I claim is:

30 1. In a spool or bobbin, a tubular barrel formed of rolled cardboard or the like, at least one end of which is formed with a generally conical flared out flange, a base of wood, or the like, formed with a generally cylindrical orifice fitting upon the said barrel and a generally conical seat extending outwardly from said orifice upon which seat the external surface of said flared out flange is seated, the outer end of said conical seat being bounded by an orifice extending to the end of the base and a bushing of wood or the like fitting tightly in the second mentioned orifice and having a conical end conforming to the internal surface of said flared out flange on the barrel tube, whereby a composite spool or bobbin is formed in which the barrel tube is firmly interlocked with the base and the base and bushing entirely enclose and conceal the end of said barrel tube.

2. In a spool or bobbin, a tubular barrel formed of rolled cardboard or the like, at least one end of which is formed with a generally conical flared out flange, a base of wood, or the like, formed with a generally cylindrical orifice fitting upon the said barrel and a generally conical seat extending outwardly from said orifice and upon which the external surface of said flared out flange is seated, the outer end of said conical seat being bounded by an orifice extending to the end of the base, and a bushing of wood or the like fitting tightly in the second mentioned orifice having a conical end conforming to the internal surface of said flared out flange on the barrel tube and having its outer end in the plane of the outer end of the base, whereby a composite spool or bobbin is formed in which the barrel tube is firmly interlocked with the base and the base and bushing entirely enclose and conceal the end of said barrel tube and form a continuous end surface of wood or the like.

70 3. In a spool or bobbin, a tubular barrel formed of rolled cardboard or the like, at least one end of which is formed with a flared out flange, a base of wood, or the like, formed with a generally cylindrical orifice fitting upon the said barrel

and a seat extending outwardly from said orifice upon which seat the external surface of said flared out flange is seated, the outer end of said seat being bounded by an orifice extending to the end of the base, and a bushing of wood or the like fitting tightly in the second mentioned orifice and having an end conforming to the internal surface of said flared out flange on the barrel tube, whereby a composite spool or bobbin is formed in which the barrel tube is firmly interlocked with the base and the base and bushing entirely enclose and conceal the end of said barrel tube.

4. In a spool or bobbin, a tubular barrel formed of rolled cardboard or the like, at least one end of which is formed with a flared out flange, a base of wood, or the like, formed with a generally cylindrical orifice fitting upon the said barrel and a seat extending outwardly from said orifice upon which the external surface of said flared out flange is seated, the outer end of said seat being bounded by an orifice extending to the end of the base, and a bushing of wood or the like fitting tightly in the second mentioned orifice and having an end conforming to the internal surface of said flared out flange on the barrel tube and having its outer end in the plane of the outer end of the base, whereby a composite spool or bobbin is formed in which the barrel tube is firmly interlocked with the base and the base and bushing entirely enclose and conceal the end of said barrel tube and form a continuous end surface of wood or the like.

5. In a spool or bobbin, a tubular barrel formed of rolled cardboard or the like, at least one end of which is formed with a generally conical flared out flange, a base of wood, or the like, formed with a generally cylindrical orifice fitting upon the said barrel and a generally conical seat extending outwardly from said orifice upon which seat the external surface of said flared out flange is seated, the outer end of said conical seat being bounded by an orifice extending to the end of the base, and a bushing of wood or the like having a part extending into and fitting tightly within the bore of the tubular barrel and having another part fitting tightly in the second mentioned orifice, the bushing between the parts mentioned being formed to conform to the internal surface of said flared out flange on the barrel tube, whereby a composite spool or bobbin is formed in which the barrel tube is firmly interlocked with the base and the base and bushing entirely enclose and conceal the end of said barrel tube.

6. In a spool or bobbin, a tubular barrel formed of rolled cardboard or the like, at least one end of which is formed with a flared out flange, a base of wood, or the like, formed with a generally cylindrical orifice coaxial with said barrel and a seat extending outwardly from said orifice upon which seat one surface of said flared out flange is seated, the outer end of said seat being bounded by an orifice of larger diameter than said first mentioned orifice, and a bushing of wood or the like fitting tightly in the second mentioned orifice and having an end conforming to the other surface of said flared out flange on the barrel tube, whereby a composite spool or bobbin is formed in which the barrel tube is firmly interlocked with the base and the base and bushing entirely enclose and conceal the end of said barrel tube.

JOHN EDWARD LOCK.
